W. T. BAILEY
FIREPLACE BASKET

Filed Jan. 24, 1928

Inventor

W.T.Bailey

By Watson E. Coleman
Attorney

UNITED STATES PATENT OFFICE.

WILLIAM T. BAILEY, OF NASHVILLE, TENNESSEE.

FIREPLACE BASKET.

Application filed January 24, 1928. Serial No. 249,167.

This invention relates to fireplace baskets and it is an object of the invention to provide a basket of this kind constructed in a manner permitting it to be readily placed within a fireplace irrespective of the relative spacing or varying lengths of the conventional frame lugs.

The invention also contemplates a basket of this kind constructed in a manner permitting it to be properly applied within a fireplace frame and more especially through the medium of a pair of spaced hook members carried by the end portions of the basket with each of the lower hook members provided with an open portion to facilitate the requisite application or removal of the basket with respect to the fireplace frame lugs without hinderance or obstruction being offered by the bottom portion of the basket.

The invention consists in the details of construction and in the combination and arrangement of the several parts of my improved fireplace basket whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view in rear elevation of a fireplace basket constructed in accordance with an embodiment of my invention and in applied position;

Figure 2 is a view in side elevation of the basket as herein disclosed;

Figure 3 is a detailed sectional view taken substantially on the line 3—3 of Figure 1 with the associated fireplace structure being diagrammatically indicated by broken lines.

As disclosed in the accompanying drawing, B denotes a fireplace basket of a conventional design and any requisite dimensions and including a vertically disposed front portion 1 and a rearwardly and substantially horizontally disposed bottom portion 2.

As is particularly illustrated in Figures 1 and 3, it is to be noted that the bottom portion 2 terminates inwardly of the ends of

the front portion 1 for a purpose to be hereinafter mentioned.

The upper portion of each of the end bars or members 3 of the front portion 1 of the basket is provided with a rearwardly disposed and downwardly facing hook member 4 which, when the basket B is in applied position, is adapted to be engaged over an upper supporting or frame lug 5. At each side of the front portion 1 of the basket and at the lower part thereof is an upwardly facing hook member 6 substantially in alignment with the adjacent upper hook member 4. The lower portion of the hook member 6 is provided with a laterally and downwardly disposed offset portion 7 which is secured to the basket at a point inwardly of the adjacent end bar or member 3 and preferably at a point adjacent to the junction of the front portion 1 with the bottom portion 2 of the basket.

Each hook member 6 is adapted to coact with the lower supporting or frame lug 8 and for which reason the bill of the hook 6 is of such length to readily compensate for varying spaces of the frame lugs, and it will also be understood that the structure of each of the hook members 4 and 6 is such as to readily engage without hinderance or obstruction frame lugs of differing lengths.

It is also to be noted that the offset portion 7 of each of the hook members 6 results in the bill of such hook coacting with the adjacent side member or bar 3 to provide what might be termed a slot 9 open at both ends and as the bottom portion 2 of the basket B terminates inwardly of the lower open portion of the slot 9, it will be readily noted that the hook member 6 may readily engage with a bottom frame lug 8 upon a substantially direct downward movement of the basket.

From the foregoing description it is thought to be obvious that a fireplace basket constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carry-

ing out my invention in practice except as hereinafter claimed.

I claim:

1. A fireplace basket having an upstanding front portion and a substantially horizontal bottom portion, hook members carried by the opposite extremities of the upstanding front portion, a hook at each end being vertically spaced and disposed inwardly, the bills of the hook members at each extremity being disposed one toward the other.
2. A fireplace basket having hook members at the opposite extremities thereof, said hook members at each extremity being arranged in pairs and vertically spaced, the bills of each pair of hook members being disposed one toward the other.

3. A fireplace basket having an upstanding front portion and a substantially horizontal bottom portion, hook members carried by the opposite extremities of the upstanding front portion, a hook at each end being vertically spaced and disposed inwardly, the bills of the hook members at each extremity being disposed one toward the other, the bottom portion of the basket terminating inwardly of the ends of the front portion of the basket, the lower parts of the bottom hook members being inwardly and laterally offset to provide a bottom entrance opening for each of the bottom hook members.

In testimony whereof I hereunto affix my signature.

WILLIAM T. BAILEY.
